WORTHY C. BUCKNAM, OF JERSEY CITY, NEW JERSEY, ASSIGNOR TO DAVIS-BOURNONVILLE COMPANY, OF NEW YORK, N. Y., A CORPORATION OF NEW YORK.

GAS CUTTING-MACHINE.

1,324,007.

Specification of Letters Patent. Patented Dec. 2, 1919.

Application filed February 19, 1919. Serial No. 278,040.

To all whom it may concern:

Be it known that I, WORTHY C. BUCKNAM, a citizen of the United States, and resident of Jersey City, in the county of 5 Hudson and State of New Jersey, have invented a new and useful Gas Cutting-Machine, of which the following is a specification.

The object of this invention is to provide 10 a simple, small, compact, and readily portable machine for cutting various shapes and openings in metal or for cutting any desired or irregular course by means of gases. The invention is specifically an improvement 15 upon and within the apparatus disclosed in my prior Patents 1,059,271 and 1,059,329, of April 15, 1913. The preferred embodiment of the present improvement comprises a standard bearing an arm or 20 frame jointed for universal horizontal movement, a torch and a rotary driven magnetic tracer carried by the arm in vertical axial alinement, and a templet over the arm for coöperation with the tracer. Various other 25 aspects and features of the invention will become apparent as the specification proceeds.

In the drawings:

Figure 1 is a side elevation; 30 Fig. 2 is a plan; and

Fig. 3 is a detail vertical section at the region of the magnetic tracer.

The machine has a base 1 with a pedestal or standard 2 bearing a continuation post 3. 35 An arm section 4 of a jointed arm or frame is pivotally mounted on the post 3 by means of a bracket piece 5. Another arm section 6 is knuckle-jointed at 7 to a bracket piece 6^a on the end of the section 4, the two arm sections being adapted to assume various angular relations in the operation of the machine. The free end of the arm section 6 carries a yoke, consisting of upper and lower castings 8 and 9. The lower yoke portion 9 has a 45 vertical tubular terminal 10, constituting a holder for a cutting torch 11 of standard construction. The torch can be raised and lowered in this holder by a hand-wheel 12 operating a rack and pinion in the customary manner.

An electric motor 13 is planted on a platform 14 on the arm section 6. A worm 15 on the projecting armature shaft meshes with a worm wheel 16 on the lower end of a 55 short vertical shaft 17 journaled in bearing

lugs 18 on the yoke member 8. On the upper end of said shaft is a worm 19 engaging a worm wheel 20 on a horizontal shaft 21 journaled in a suitable bearing on the same part.

A bevel gear 22 on the opposite end of the shaft 21 meshes with a bevel gear 23 on a vertical sleeve 24, which turns about a fixed vertical shaft 25. The said fixed shaft 24 passes through lugs 26 and 27 of the yoke member, to the lower of which it is pinned, as indicated at 28. The sleeve 24 is suitably journaled in the lug 26 and about the shaft 25 and is pinned or otherwise connected to a cylindrical magnet core member 29. The fixed shaft 25 extends upward through said core member and is provided at its upper end with a reduced threaded extremity 30, which screws into an opening in the top of a tubular magnet body 31, the magnet body and the energizing coil 32 thereon being thus supported from the universally movable arm or frame and being stationary with respect to the core member 29, which is rotatable by the motor and 70 gearing.

The lower end of the core member 29 which projects below the magnet body is formed as a knurled roller 34 to travel upon the vertical boundary or edge 35 of a templet 36. The templet is clamped at the top of the standard post 3, and in this particular instance the guiding surface or edge 35 is an internal boundary formed by an opening in the templet plate.

From the foregoing it will be perceived that the feed roller or tracer 34 will adhere magnetically to the boundary of the templet, which is of magnetic material, and when the motor is started will automatically proceed through the intended course at appropriate uniform speed for cutting. This speed may be varied through a known adjustable governor contained in an extension case 37 on the motor, or otherwise.

The tracer roller and the jet delivering means of the torch being in vertical axial alinement, the torch operates simultaneously through the same path as the roller. In the illustrated embodiment the result is to 105 cut a desired opening in a plate *a*, which is a duplicate of the templet opening.

In order to enable the cut to be started off the desired course, and in this instance in the cut-out disk, which is scrap, a switch-

piece 38 is pivoted at 39 on the templet, so as to be capable of projecting into the templet opening. In this position, it is sustained by a stop pin 40 on the templet. The 5 tracer or feed roller in starting is placed against the forward inclined edge 41 of the switch-piece, the magnet circuit is completed to cause it to adhere, the heating jet or jets of the torch are then turned on and 10 lit, and after a spot in the plate *a* becomes heated, the cutting oxygen jet is turned on and a hole blown through. At the same time the motor is started, and the tracer rolls along the edge of the switch-piece to 15 the boundary of the templet opening, and thence along the same, causing the cut in the underlying plate to proceed in similar manner. When the roller comes around to the back of the switch-piece, it pushes it out of 20 the way, to the dotted line position of Fig. 2. In order to prevent the magnetic roller adhering to the switch-piece at this time, a strip 42 of brass or other non-magnetic material is secured along the back of the 25 piece.

The electric circuits are not shown, as being obvious matters. The wires of the magnet circuit are connected to binding-posts 43 on the magnet, and the circuit is controlled 30 by a switch 44 on the base. Another switch 45 controls the motor circuit. This circuit may also be controlled by a switch 46 on the torch, connected with the valve controlling the cutting oxygen, the handle of which is 35 seen at 47, as disclosed and claimed in my Patent 1,118,183, of November 24, 1914.

Other embodiments of the invention may be designed. It will be understood that the templet shown in the drawings is removable 40 and can be replaced with other forms of templet appropriate for other specific forms of cut.

What I claim as new is:

1. A gas-cutting machine comprising a 45 support, a frame supported therefrom jointed for universal movement in a plane, a downwardly-directed torch carried by the frame, and a driven tracer connected with the frame and located over the torch.

50 2. A gas-cutting machine comprising, in combination, a support, a frame supported therefrom jointed for universal movement in a plane, a downwardly-directed torch carried by the frame, a templet over the torch, 55 and mechanical feed means carried by the frame to coöperate with said templet.

3. A gas-cutting machine comprising, in combination, a standard, a frame supported therefrom jointed for universal movement 60 in a plane, a downwardly-directed torch car-

ried by the frame, a templet supported from the standard above the frame, and means for propelling the torch in a predetermined path having a wheel on the frame in axial alignment with the torch coöperative with 65 the templet.

4. A gas-cutting machine comprising, in combination, a support, a frame supported therefrom jointed for universal movement in a plane, a torch carried by the frame, a 70 stationary templet, and means for propelling the torch having a wheel on the frame in axial alignment with the torch coöperative with the templet.

5. A gas-cutting machine comprising, in combination, a support, a frame supported therefrom jointed for universal movement in a plane, a torch carried by the frame, a stationary templet, a magnetic rolling tracer carried by the frame in axial alignment with 75 the torch to coöperate with the templet, and means for driving the tracer.

6. A gas-cutting machine comprising, in combination, a support, a pivotally jointed arm pivotally supported on the support, a 80 torch carried by the arm, a stationary templet, and a driven tracer wheel on the arm in axial alignment with the torch.

7. A gas-cutting machine comprising, in combination, a support, a jointed arm on the support, a yoke on the arm, a torch mounted in one part of the yoke, a rolling tracer mounted in the other part of the yoke in axial alignment with the torch, a templet, and means for driving the tracer. 90

8. A gas-cutting machine comprising, in combination, a carrier universally movable in a plane, a torch and a driven magnetic tracer in axial alignment in the carrier, a templet, and a movable switch-piece associated with the templet whereby the cut is started off the true course. 95

9. A gas-cutting machine comprising, in combination, a carrier universally movable in a plane, a torch and a driven magnetic tracer in axial alignment in the carrier, a 100 templet, a pivoted switch-piece associated with the templet whereby the cut is started off the true course, and an abutment for sustaining the switch-piece in the starting position, the switch-piece being adapted to be moved automatically out of the way by the tracer toward the conclusion of the cut. 110

10. In a gas-cutting apparatus, the combination with a torch carrier, of a driven magnetic feed or tracer wheel journaled on the carrier, and a non-rotary magnet body independently supported on the carrier. 115

WORTHY C. BUCKNAM.

DISCLAIMER

1,324,007.—*Worthy C. Bucknam, Jersey City, N. J. GAS-CUTTING MACHINE.*
Patent dated December 2, 1919. Disclaimer filed February 18, 1933, by the
assignee, *Air Reduction Company, Incorporated.*

Hereby enters this disclaimer to that part of the claim in said specification which
is in the following words, to wit:

“1. A gas-cutting machine comprising a support, a frame supported therefrom
jointed for universal movement in a plane, a downwardly-directed torch carried by
the frame, and a driven tracer connected with the frame and located over the torch.

“2. A gas-cutting machine comprising, in combination, a support, a frame sup-
ported therefrom jointed for universal movement in a plane, a downwardly-directed
torch carried by the frame, a templet over the torch, and mechanical feed means
carried by the frame to cooperate with said templet.”
